COMBINED FLASHLIGHT AND CIRCUIT TESTER

Ernest Otto Scheerer, Linden, N. J.

Application May 18, 1935, Serial No. 22,278

6 Claims. (Cl. 175—183)

This invention relates to an improved device for testing electrical circuits, and one of its objects is to provide an attachment for flashlight cases, which can be operated to test the condition 5 of an electrical circuit, the flashlight lamp serving as an indicator for showing the action of the current produced by the battery in flowing through the circuit.

Another object of the invention is the provision 10 of an attachment for flashlight cases, which includes a windable conductor wire, and means whereby this wire can be extended from the end of the flashlight case and be connected to one terminal or portion of an electrical circuit, and the 15 current of the flashlight battery used to operate the circuit, if it is active, and the condition of the circuit observed through the operation of the flashlight bulb or lamp.

Another object of the invention is the provision 20 of an attachment for flashlight cases, including a self winding conductor wire or element, one end of which is electrically connected to one end of the flashlight battery, and the other end of which is equipped with a metal connector or clip also normally connected electrically to the flashlight 25 case, but detachable therefrom to permit of distant connection to a portion of a circuit to be tested, whereby the dry cells of the flashlight case may be used, in combination with the self winding conductor to make working tests of 30 motors, bells, lighting circuits, etc.

A still further object of the invention is the provision of an attachment of this kind, with means for operating a telephonic receiver from the dry cells, so that sensitive working tests may be made under conditions, offering higher circuit resistance, which would not be very responsive to the flashlight bulb.

Another object of the invention is the provision 40 of a combined flashlight and testing device, which will permit of the free use of the flashlight for all desired purposes, and permit of the use of the dry cells of the flashlight to test electrical circuits, either by using the flashlight lamp alone, 45 or in conjunction with the telephonic receiver to show the activity or inactivity of the circuit subjected to test.

With the above and other objects in view the invention consists in certain new and useful combinations, constructions, and arrangements of parts, clearly described in the following specification, and fully illustrated in the accompanying drawing, in which:

Fig. 1 is a side view of the improved device. 55 Fig. 2 is a longitudinal sectional view, through the rear end of the testing device. Fig. 3 is a transverse sectional view, taken on line 3—3 of Fig. 1, looking in the direction of the arrows. 60 Fig. 4 is a cross sectional view, taken on line

4—4 of Fig. 1, looking in the direction of the arrows.

Fig. 5 is a detail showing the relationship of the terminals of the cup. Fig. 6 is a detail showing the bulb end of the device. 5

Referring to the drawing 5 designates the cylindrical metal shell of the flashlight case, on the forward end of which the reflector 6 is screw threaded or otherwise coupled. The usual incandescent lamp 7 is detachably threaded in this 10 case, so that its usual metal shell will have electrical contact with the metal case or shell 5, and its central electrode 8 may be electrically connected with the central electrode of the adjacent dry cell 9, by means of the manual switch 10, 15 which slides in the usual manner.

The rear end of the metal case 5 is formed with the usual screw threads 11, normally engaged by the usually detachable metal cap which is fitted on standard pocket flashlight cases. In 20 substitution of this closure cap, not shown, I provide an attachment, which includes a metal case or cap 12, which is formed with screw threads to engage the screw threads 11. This metal case or cap 12 is equipped with a central fixed 25 guide 13, formed of fibre or other suitable insulating material, in which the metal pin 14 is arranged to slide. This guide or post carries the metal spring 15, the inner end of which is extended through the wall of the tubular guide 30 13 to have electrical contact with the metal pin 14. A coil spring 16 is arranged on this pin, one end of which engages the inner end of the guide 13, and the other end of which engages the head 17 formed on the inner end of the pin. 35 This head projects through a central opening formed in the fibre or insulating cup 18, so that electrical contact may be established with the rear end of the adjacent dry cell.

A winding reel or spool 19 is arranged over 40 the winding spring 15 and is connected to the outer end thereof. On this reel or spool the flexible wire or conductor 20 is wound, the inner end of this wire being connected to the spring 15 to conduct electricity from the dry cells, 45 through the pin, and the spring, to the spring or other metal clip 21, attached to the end of the wire 20. This wire is covered with rubber or other thin insulation, so that when the wire is pulled through the hole 22 in the case 12 the 50 metal terminal clip or connector 21 will not be in circuit with the case 12.

The case 12 is equipped with a binding post 23, located adjacent to the hole 22. When the clip 55 is pulled away from the flashlight case and placed in metallic contact with a portion of any electrical circuit, the binding post 23 may be connected to another portion or terminal of the circuit to be tested. With the manual switch of the flashlight case in closed position, current will flow 60

from the dry cells through the flexible wire, to the clip 21, through the circuit to be tested, if the same is active or not broken, to the post 23, to the case 12, to the case 5, to the lamp 7, back 5 to the dry cells.

In this circuit arrangement the lamp 7 will be illuminated when the circuit tested is found alive. When the circuit to be tested has a high resistance, an ear piece or telephonic receiver 24 may 10 be used. This ear piece may be connected to the case 12 by means of the ring frame 25, in such manner that it can be detached from the case 12, or swung outwardly thereof. This ear piece is provided with a binding post 26 which 15 is in circuit with one end of the enclosed winding of the receiver magnet, and is also provided with another binding post 27 which is in circuit with the other end of the receiver winding.

When the clip 21 is in metallic contacting 20 engagement with the case 12, the flashlight may be employed in the ordinary manner.

The ring frame 25 provides ground electrical connection between the receiver or ear piece and the case 12, when the receiver is attached to 25 the case 12.

The combined device is particularly useful for electricians and mechanics, who must inspect electrical circuits in different buildings and places, and who cannot carry around costly and 30 heavy equipment for this purpose. The equipment is designed to provide a compact unit, which will serve to illuminate a field of work, or to test any circuit, either by using the lamp of the flashlight as an indicator, or by using the 35 more sensitive telephonic ear piece or receiver.

The testing unit is so constructed that it may be mounted in place of the usual closure cap on the end of the flashlight case or barrel. It does not interfere with the operation of the 40 flashlight, and provides means for making contact with portions of a circuit which are widely separated.

In Fig. 5 I show an electrical lamp, consisting of an inner glass bulb 40, which is equipped with an incandescent filament 41, and the usual terminal electrical connector cap 42 and the central electrode 43. An additional bulb 44 is arranged around the bulb 40, and sealed at its point of connection therewith at 45 to provide a space 46 between the two bulbs, which is exhausted to 50 provide a vacuum between the two bulbs. This results in reducing the radiation losses of heat from the illuminating filament 41, so that with less consumption of current the filament can be properly energized to give maximum illumination, or with the same current supply increased 55 illumination will be obtained. The effect of this conservation of the heat energy produced by the flow of the current, is to increase the life and efficiency of the dry battery used for operating the improved bulb.

Having described my invention I claim:

1. The combination with a flashlight having a case, a lamp on one end of the case, dry cells within the case, a metal cap mounted on the end of the case, means carried by the cap to establish electrical connection with the dry cells, a self-winding drum arranged in the cap, a flexible electrical conductor connected to the drum, a clip on the end of the flexible conductor, said 65 drum and the conductor being electrically connected to the means, and a switch for controlling the circuit through the dry cells and lamp,

whereby the electrical conductor may be employed for making tests of circuits portions of which are widely separated from each other.

2. A device of the character described adapted for use with a hand electrical flashlight having a casing and a lamp at one end of said casing and dry batteries within the casing electrically connected to the lamp comprising in combination a cap detachable on the end of the case and provided with a spring pressed contact member 10 engaging the dry cell adjacent thereto, a spring rotated winding drum having electrical connection with the spring pressed contact member, a flexible insulated conductor connected electrically to the drum and windable thereon, a terminal connector connected electrically to the conductor and adapted to be electrically connected with the cap when disposed against the same, and means for controlling the circuit 15 through the lamp.

3. A hand electrical testing attachment for hand electrical flashlight cases, consisting of a metal case adapted to be coupled to the end of a standard flashlight case and provided with a spring pressed electrical contact member engageable with the adjacent dry cell of the flashlight case, a ring frame having electrical connection with the metal case, a telephonic receiver mounted on the ring frame for detachment from the metal case, and means for making connection 25 between the telephonic receiver and the flashlight case, whereby the receiver may be placed in electrical circuit with the flashlight and operated by the batteries thereof.

4. An attachment for flashlights consisting of 30 a case having a coupling element to engage a flashlight case, a spring rotated drum within the first case, a flexible conductor cord connected with the drum and having a connecting element secured to one end thereof adapted to 40 be normally held against said first case to permit of the ready extension of said conductor, means for supplying current from a dry battery of a flashlight case connected with the first case to 45 said conductor, means for establishing electrical contact between said first case and said flashlight case and an audible signal element pivotally mounted on said first case and having terminal connections to permit circuit connection being established with the battery of the first case.

5. A device of the character described adapted for use with a flashlight containing a casing, batteries and a bulb comprising in combination a cap of a diameter and shape to fit upon the end of the flashlight as a cap and having means for physical attachment to said cap, a contact within said cap adapted to engage one terminal of the battery, a spring reel mounted co-axially with said cap, a conductor mounted on said reel and in rotatable contact with said contact, said conductor extending through an opening in said cap to the exterior and being provided with a terminal and a second terminal carried by said cap connected to said casing.

6. A device in accordance with claim 5 and 65 provided with a telephone receiver mounted on said cap having one end of its magnet connected to the terminal of the battery to which said flexible conductor is not connected and having its other end provided with a terminal exterior to 70 the cap.

ERNEST OTTO SCHEERER.
